GOLD RECOVERY DEVICE

Albert Trayman, Seattle, Wash.

Application September 7, 1935, Serial No. 39,598

5 Claims. (Cl. 209—184)

My invention relates to the recovery of gold, particularly fine gold known as flour gold, from goldbearing sand.

It is well known that certain sands contain considerable quantities of gold, but in such fine form that it is difficult and, practically speaking, uneconomical to separate the gold from the sand by any process heretofore known. It is an object of the present invention to provide a process and an apparatus whereby such gold may be profitably recovered from such sand.

It is a further object to provide a process and apparatus for the purpose stated which is capable of continuous operation, and which is therefore economical of the heat and power required.

With these and other objects in mind, as will appear hereafter, my invention comprises the novel process, and the novel apparatus and parts thereof, as shown in the accompanying drawing, described in this specification, and as will be more particularly defined by the claims which terminate the same.

In the accompanying drawing I have shown typical apparatus embodying my invention in diagrammatic form.

Figure 1 is a general vertical section through the apparatus, illustrating the operation of the process.

Figure 2 is a general plan view of the apparatus.

Figure 3 is a transverse section substantially on the line 3—3 of Figure 1.

Essentially the process comprises the drying of the gold-bearing sand until it will readily break up or fall apart into individual granules, and preferably by the application of heat to the sand, which heat is subsequently recovered, then forcing the gold-bearing sand beneath the surface of molten lead and its thorough admixture with the lead, so that when the sand is released, being of less specific gravity than the lead, it will float to the top, but the gold, being heavier, will remain in the lead, and will drop to the bottom of the container, and the subsequent removal of the sand from the surface of the molten lead. During this process there should be a continuous stirring of the mass to facilitate and encourage the breaking up of lumps of sand into individual granules, for by this means the gold may be segregated from the sand, and the individual granules of sand will, upon being divested of their gold, rise to the surface of the molten lead, where they can be removed as part of a continuous process, and the gold can from time

to time be drawn off from the bottom of the lead pot.

The apparatus illustrated is merely diagrammatically shown as typical of suitable apparatus for carrying out the process, and in so far as the process is concerned, the apparatus may differ from that shown. It comprises essentially a sand drying device 1, a pot 2 for the molten lead, feed means, such as the feed screw 3, for receiving sand from the drying device 1 and feeding it below the surface of the molten lead in the pot 2, and in addition there may be provided a scraper 4 for removing the sand from the surface of the molten lead, an agitator 5 within the lead pot 2 to assist in mixing the sand and lead, and a spout 20 for withdrawing the collected gold, together with a portion of the molten lead to act as a vehicle for the gold.

The drier 1 may comprise a hopper 10, into which the sand is dumped, a dome 11 within the hopper and provided with suitable means to heat it, as for example the oil burner 12 and outlet flue 19, baffles 13 to spread the sand out into a comparatively thin layer, and a baffle 14 which is adjustable and which serves as a gate to admit sand, when sufficiently dried, from the drying compartment into a chute 15.

After delivery by means of the chute 15, the sand passes into a conduit 39, whence it is delivered into a tubular housing 31 containing the feed screw 3. The latter is suitably rotated, for example by a motor 32 driven through gearing within the gear casing 33, to advance the sand down to the lower part of the pot 2. This pot contains molten lead L, and the upper part of the pot is connected to the upper part of the feed screw housing 31 by means of a passage or conduit 23, so that lead from the upper part of the pot 2 is carried over to the feed screw housing, and is continuously mixed with the sand as the sand is being advanced by the feed screw into the lower part of the pot 2. This mixing action, in addition to thoroughly intermixing the lead and sand, serves to break up the sand into individual granules, so that when it is released from the feed screw at the bottom of the pot the sand, being of lower specific gravity than the lead, will float upwardly toward the surface of the lead in the pot.

Within the pot the member 5 is located to spread the lead into a comparatively small annular body. The member 5 is preferably rotatable, a motor 50 connected through gearing within the gear casing 51 being shown for the purpose, and

it carries cleats or projections 52 upon its surface which further assist in mixing the sand with the lead, as the sand floats upwardly, and in breaking up the sand into individual granules.

5 The gold being heavier than the lead, it will remain in the bottom of the pot 2, where it can be drawn off from time to time through the spout 20, suitable valve or closure means 29 being provided to control the removal of the 10 gold and lead.

15 The pot, and preferably also the feed screw housing, are supported suitably within a chamber 6, which may be heated by suitable means such as the burner 60, whereby the lead is kept in a molten state at all times.

20 As the sand rises to the surface of the molten lead, and is forced above the surface by the buoyancy of sand from below, it will pass over an inwardly directed flange 61, which prevents splattering of the molten lead, and will engage the baffle or scraper 4 as the sand is rotated by the rotary body 5, and the scraper will effect removal of the sand from above the surface of the lead, the sand running off down the chute 62.

25 Little lead is lost in this process, inasmuch as it will substantially all drain off the sand after the sand has passed above the normal surface level of the molten lead, but to replace any lost, or to charge the pot, I may provide a charging 30 hopper 24, suitably covered, whereby pigs of lead may be fed into the system from time to time, where, upon melting, it will mingle with the lead flowing through the conduit 23.

What I claim as my invention is:

35 1. Apparatus for the recovery of gold from sand, which comprises a pot to contain molten lead, a rotative body disposed in said pot to leave a relatively thin unobstructed annular space for the lead and sand, spaced cleats thereon 40 moving in said annular space, but spaced from the pot, to stir up the lead and sand, and means to advance gold-bearing sand beneath the surface of the lead in said pot, whereby the sand will float upward and the gold will remain submerged.

45 2. Apparatus for the recovery of gold from sand, which comprises a pot to contain molten lead, means for receiving the gold-bearing sand and advancing it to the lower part of said pot, beneath the surface of the lead, whereby the sand will float upward, leaving the gold sub-

merged, a rotative body largely filling the pot, to leave a comparatively thin unobstructed annular space for the lead and sand, and circumferentially spaced cleats on said body, extending generally lengthwise thereof to mix the sand with the lead in said annular space.

3. Apparatus for the recovery of gold from sand, which comprises a pot to contain molten lead, an inclined and enclosed feed screw adapted to receive gold-bearing sand and to advance it to the lower part of said pot, beneath the surface of the lead, whereby the sand will float upward, leaving the gold submerged, and a passage connecting the upper part of the pot and the upper end of the feed screw enclosure, for circulation 15 of lead from the pot to the enclosure, and its admixture with the sand advanced by the feed screw prior to its delivery to said pot.

4. Apparatus for the recovery of gold from sand, which comprises a pot containing molten 20 lead, means to deliver gold-bearing sand to said pot near the bottom thereof, a body rotative about an upright axis and disposed in said pot to leave a relatively thin annular space for the lead and sand, and extending upward above the 25 surface of the lead, a circumferential flange extending inward from the top of the pot, and terminating closely adjacent to said body, to leave an annular space for the reception of sand freed from gold, and means for removing sand 30 from said annular space.

5. Apparatus for the recovery of gold from sand, which comprises a pot containing molten 35 lead, means to deliver gold-bearing sand to said pot near the bottom thereof, a body rotative about an upright axis and disposed in said pot to leave a relatively thin annular space for the lead and sand, and extending upward above the 40 surface of the lead, a circumferential flange extending inward from the top of the pot, and terminating closely adjacent to said body, to leave an annular space for the reception of sand freed from gold, a discharge passage leading from the upper side of said flange, and a baffle extending above and below said flange and lying 45 closely adjacent to said rotative body, and conforming to the contour thereof to guide the sand for movement from the said annular space between the body and the flange to the upper side of the latter, and into said discharge passage. 50

ALBERT TRAYMAN.
